United States Patent Office.

MOSSES PALMER, JR., OF LYNN, MASSACHUSETTS.

Letters Patent No. 101,155, dated March 22, 1870.

IMPROVEMENT IN SHIRT-YOKES.

The Schedule referred to in these Letters Patent and making part of the same.

Be it known that I, MOSES PALMER, Jr., of Lynn, county of Essex, State of Massachusetts, have invented a new and useful improvement in Shirt-Yokes; and I hereby declare the following a full and exact description of the same, reference being had to the accompanying drawings and to the letters of reference marked thereon.

To enable others skilled in the art to make and use my invention, I will proceed to describe its construction.

Upon the accompanying drawings—

Figure 1 is an external view of the back of my shirt.

Figure 2 represents an internal view of the same.

Figure 3 shows the scapulars, as they are made and attached to the collar-band.

Figure 4 is a horizontal section of the shirt below the collar-band.

Figure 5 shows the form of the scapular.

My invention relates to the manufacture of shirts, and consists mainly in the construction and novel arrangement of scapular-pieces designed to take the place of a yoke, thereby rendering the shirt more easy of alteration in this most difficult part to fit, improving the set of the same, and increasing the comfort of the wearer.

The letter A of the drawings designates my shoulder-piece, of the form indicated in fig. 5.

It is made double in order to afford a lining, a, as well as an external covering, b, to the cloth of the shirt proper, P, which is sewn within it.

D represents the collar-band, to which the scapulars are attached, and which holds them in position.

The scapulars are not attached to each other, but a fullness of the cloth of the shirt is allowed between them in the form of a plait, the upper edge of which is sewn to that portion of the collar-band which lies between and connects the scapulars.

This plate renders the gathering of the cloth of the shirt along the lower edges of the scapulars unnecessary, and has been marked e on the drawings.

A shirt made in this manner corresponds with the formation of the wearer's back, and adapts itself with ease to all his actions. Violent exertion of lifting and pulling will not disarrange the set of my shirt, nor can it bind the wearer.

Should any alteration be needed in the size of the neck, it will only be necessary to let out the plait to correspond with the size of the new collar-band. No change or alteration need be made in the scapulars.

What I claim as my invention, and desire to secure by Letters Patent, is—

The scapulars A A, herein described, attached to the collar-band of a shirt as a substitute for a yoke, when constructed and arranged to operate as and for the purposes herein set forth.

MOSES PALMER, JR.
